UNITED STATES PATENT OFFICE.

WILLIAM J. MATTESON, OF ST. LOUIS, MISSOURI.

WRENCH.

1,245,754.

Specification of Letters Patent.

Patented Nov. 6, 1917.

Application filed March 1, 1916. Serial No. 81,343.

To all whom it may concern:

Be it known that I, WILLIAM J. MATTESON, a citizen of the United States, residing in the city of St. Louis and State of Missouri, 5 have invented a new and useful Wrench, of which the following is a specification.

This invention relates to improvements in wrenches, and the object is to provide a wrench comprising a handle having a jaw 10 fixed thereon, in combination with a jaw movable on the handle and provided with manipulative means for adjusting and holding the same in different positions relative to the fixed jaw, the two jaws being constructed with polygonal sides so that they 15 may be engaged within the polygonal opening of a valve plug or the like and adjusted so as to effect firm engagement therewith so that the wrench may be operated to release or adjust the plug or the elements 20 with which it is engaged.

In the particular embodiment shown the two jaws of the wrench when brought together form a hexagonal head in which the 25 combined width of adjacent side edges of jaws form one of the sides of the hexagonal head of equal width with each of the other sides of the hexagonal head. The adjacent surfaces of the two jaws are flat planes so 30 that they may be engaged against the exterior walls of a nut or the like in the usual manner of wrenches, thus providing a wrench having the combined function of a nut wrench and a wrench for engagement 35 within polygonal openings for the purpose previously mentioned.

In the accompanying drawing in which I have illustrated the preferred embodiment 40 of my improved wrench,

Figure 1 is a plan view illustrating the construction and arrangement of the polygonal head composed of the fixed jaw and the adjustable jaw.

Fig. 2 is a side elevation.

Fig. 3 is a sectional view on the line 3-3 of Fig. 1.

Fig. 4 is a rear side elevation of the wrench.

Fig. 5 is an end elevation.

Fig. 6 is a sectional view on the line 6-6 of Fig. 2.

The wrench includes a metal bar 1 of substantial shape and construction having a manually engageable handle 2 in connection with one end thereof. A jaw 3 is rigid 55 with the opposite end of the bar 1 and in

the embodiment illustrated the jaw 3 is in the form of one half of a hexagonal body in which each of the side edges 4 is one half of the width of either of the side edges 5. 60 The arrangement is such that the apex formed by meeting of the side edges 5 is in the same plane with the axis of the bar 1, so that the inner wall 6 of the jaw 3 is at right angles to the axis of the bar 1. 65 Preferably the back of the jaw 3 is formed with a head 7 which extends below the bar 1 and which is adapted to be used as a hammer, or otherwise as desired.

The movable jaw 8 has an opening 70 through which the bar 1 extends and is provided with an extended portion 9 formed in integral connection with a sleeve 10 embracing the bar 1 and coöoperating with the remainder of the jaw 8 to hold or retain 75 the latter in proper position upon the bar 1. The jaw 8 is also in the form of one half of a hexagon and when the inner wall 11 thereof is in contact with the inner wall 6 of the fixed jaw 3, the two jaws constitute 80 or form an equilateral hexagon in which the side edges 12 of the jaw 8 are in alignment with the side edges 4 of the jaw 3. Thus the combined width of one of the side edges 4 of the fixed jaw and the adjacent 85 side edge 12 of the movable jaw is equal to the width of either of the side edges 5 of the fixed jaw, or either of the side edges 13 of the movable jaw.

It will be observed that the inner wall 11 90 of the movable jaw is parallel with the wall 6 of the fixed jaw and therefore is adapted to coöperate with the fixed jaw to serve as a wrench for operation of a nut or the like. It will also be observed that by moving the 95 movable jaw away from the fixed jaw the wrench may be enlarged so as to engage firmly within the polygonal opening in which it is placed.

The movable jaw 8 and the extension 9 100 thereof contain a threaded hole 14 within which the screw 15 is operatively engaged. The screw 15 is provided with a serrated wheel 16 having an axial projection 17 extending into a recess or bearing in an adjacent abutment 18 fixed to the bar 1 and arranged to prevent axial movement of the screw 15 toward the handle. The wheel 16 extends into a notch 19 in the bar 1 and said notch is of such depth that the walls 110 thereof serve as abutments limiting axial movement of the wheel and thus enabling

the screw to retain the jaw 8 rigidly in proper adjustment when engaged within a polygonal opening.

- 5 The back portion 20 of the movable jaw is preferably in the same plane with the back or head 7 of the fixed jaw, so that said two back portions may also constitute a polygonal head for engagement in smaller openings than will receive the jaws 3 and 8.
- 10 10 A wrench of this construction is especially adapted for use in adjusting and removing valve plugs from the engines of automobiles, and it is also adapted for a variety of other uses, to which the wrenches of usual construction are not applicable.

What I claim and desire to secure by Letters Patent is:—

- 20 A wrench, comprising a manipulative handle bar; jaws supported by the handle bar adapted to coöperate to engage within a polygonal recess or to engage between them a polygonal head or nut of any size narrower than the space to which said jaws may be spaced apart, and each comprising 25 one-half of a solid hexagonal body

severed at right angles to two of the side edges thereof, and presenting to the adjacent jaw a continuous straight wall at right angles to the axis of the handle bar, and the combined width of the adjacent outer side edges of the jaws being equal to the width of either of the other two sides of either jaw, one of said jaws being fixed on the handle bar and the other being movable thereon; and means for adjusting and holding the movable jaw in any desired position relative to the fixed jaw, whereby said jaws may be adjusted for engagement with the internal polygonal surfaces or with polygonal heads or nuts of any size narrower 40 than the space to which said movable jaw may be moved from the fixed jaw.

In witness whereof, I have signed this specification in the presence of two subscribing witnesses.

WILLIAM J. MATTESON.
